RUNG ASSEMBLY FOR FOLDING CHAIRS

Glenn H. Norquist, Jamestown, N. Y.

Application June 27, 1950, Serial No. 170,641

3 Claims. (Cl. 155—141)

1

This invention relates to rung assembly for folding chairs and more particularly to folding chair having a back section and a front leg section hingedly connected to the seat section which incorporates a chair strengthening rung frame hingedly connected to the legs of the back section and front leg section, and which is automatically foldable with the folding movement of the seat section and front leg section to and from collapsed position.

Folding chairs constructed in accordance with this invention generally comprise a back section presenting a pair of rear legs connected by a rear rung and leg extensions which extend above the seat section to which a back rest is secured. The seat section generally comprises an apron frame to which a padded seat panel is secured, the seat section being hingedly connected to the back section by a pair of rear hinge assemblies which permit folding movement of the seat section into substantial parallelism with the back section. The front leg section comprises a pair of front legs connected at the upper portions thereof by a front rung which is out of reach of the feet of the chair occupant. The front leg section is hingedly connected to the seat section by a pair of front hinge assemblies to permit folding movement thereof into substantial parallelism with the seat section. Latching mechanism is provided which is designed to securely latch the front leg section to the seat section and thus maintain the chair in rigid erect position.

Many folding chairs heretofore constructed are equipped with a front rung which is pivotally connected to the front chair legs within the reach of the feet of the seated chair occupant. In such prior art structures, the front rung is in the way of comfortable placement of the feet of the chair occupant partially under the chair seat, and additionally induces the chair occupant to hang the heels of his shoes on the pivotally supported front rung which often results in breaking or damaging the front chair rung and thus rendering the chair useless for further service.

An important feature of this invention is the provision of a rung frame which pivotally connects the rear legs to the front legs of the chair in a manner to stiffen and strengthen the chair structure. The rung frame comprises a pair of side rungs which are rigidly connected by one or more transversely extending connecting bars located some distance under the seat section when the chair is erected and thus out of the reach of the feet of the chair occupant. The rear end of each side rung is hingedly connected to the adja-

2

cent rear leg of the back section by a simple hinge assembly which is substantially concealed from exterior view when the chair is erected. The front end of each side rung is likewise hingedly connected to the adjacent front chair leg by a front hinge assembly which is also substantially invisible when the chair is in erected position. These hinge assemblies are so constructed as to permit the adjacent ends of each side rung to substantially abut the adjacent face of the chair legs and to reveal only a hair line seam therebetween when the chair is in erected position, and yet permit automatic folding of the rung frame with the folding movement of the front leg section.

The front and rear hinge assemblies which connect the rung frame to the chair legs may be similar in construction, and each may be formed from a pair of relatively thin metal leaf plates shaped in the form of a crescent which are buried in conforming grooves in the side rungs and chair legs. Each leaf plate presenting a relatively small head portion projecting therefrom which are hingedly connected by a hinge rivet and designed to seat within the corner defined by the adjacent face of the chair leg and the adjacent face of the side rung.

Folding chairs having this improved rung frame associated therewith are normally out of the reach of the feet of the chair occupant so as to permit comfortable seating in the erected chair with the feet of the chair occupant partially under the chair seat.

Other objects and advantages of this invention will become apparent as the disclosure proceeds.

Although the characteristic features of this invention will be particularly pointed out in the claims, the invention itself, and the manner in which it may be carried out, may be better understood by referring to the following description taken in connection with the accompanying drawings forming a part hereof, in which

Fig. 1 is a perspective view of the folding chair equipped with the improved hinged rung frame as the same appears in set up position.

Fig. 2 is an elevational view of the folding chair as it appears when in collapsed position.

Fig. 3 is a perspective view of one of the rung hinge assemblies shown in full lines as the same would appear when the chair to which it is attached is in set up position, one of the hinge leaves being shown in dotted lines as the same would appear when the chair to which it is attached is in folded position.

Fig. 4 is a sectional view through the hinge as-

sembly as the same would appear when looking in the direction of the arrows 4—4 of Fig. 3.

Fig. 5 is a cross-sectional view taken through the front and rear legs of the set up chair as the same would appear when viewed in a horizontal plane, this view showing the manner in which the rung frame is hingedly connected to the chair legs.

Fig. 6 is a fragmentary elevational view showing one of the rung hinge assemblies attached to the end of one of the side rungs and the adjacent front chair leg, certain parts being broken away to illustrate certain details of the construction; and,

Fig. 7 is a fragmentary cross-sectional view taken through one of the side rungs as the same would appear when viewed along line 7—7 of Fig. 6, this view showing further details of the manner in which the associated rung hinge assembly is attached to the side rung and the adjacent chair leg.

Similar reference characters refer to similar parts throughout the several views of the drawings and specification.

Folding chairs constructed in accordance with this invention, as shown in the accompanying drawings for purposes of illustration, generally comprise a rear leg and back section 1 hingedly connected to a seat section 25 by a pair of rear hinge assemblies 30, and a front leg section 5 hingedly connected to the seat section 25 by a pair of front hinge assemblies 35.

The rear leg and back section 1 may be constructed to provide a pair of rear legs 2 having leg extensions 2' to which a back rest 3 is secured. The rear legs 2 may be secured together by a rear leg connecting rung 4 so that the rung 4 and the back rest 3 secured to the legs 2 and leg extensions 2' provide a strong and rigid back section for the chair. It will be appreciated that the rear leg extensions 2' may be formed as an integral part of the rear legs 2 and may be made of wood or metal shaped to any desired artistic contour. The back rest 3 may be made from artistically carved or shaped wood or metal and if desired may be padded as indicated in Figs. 1 and 2 of the drawings.

The front leg section 5 comprises a pair of front legs 6 which are secured together by a front leg connecting rung 7. The front legs 6 may be given any desired shape or contour and may be made from either wood or metal. It will be noted that the connecting rung 7 is connected to the upper half portion of the front legs 6 as shown in Figs. 1 and 2 so that the chair occupant cannot readily place his feet on the rung 7 in a manner to subject the same to unusual strain.

The seat section 25 is constructed to provide a seat frame which may be made from either wood or metal. The seat frame as shown in Figs. 1 and 2 for purposes of illustration may comprise a front apron member 26, a rear apron member 27, and a pair of side apron members 28 connecting the front and rear apron members 26 and 27 to provide a depending apron frame. A seat panel 29, which may be padded and covered with covering material such as leather, textile fabric, or suitable plastic sheeting material which is tough and wearable, is suitably secured to the apron frame.

The rear leg and back rest section 1 is hingedly connected to the apron frame of the seat section by a pair of rear hinge assemblies 30 as shown more particularly in Figs. 1 and 2. Each rear hinge assembly 30 may be simply constructed

from stamped metal parts to provide a seat bracket 31 of generally angular form and presenting a horizontal leg 31' and a vertical leg 32. A hinge arm 33 is pivotally connected as by a pivot rivet 34 to the upper end of the vertical leg 32 of the rear seat bracket. The horizontal leg 31' of each rear hinge bracket 31 is secured to the inside face of the adjacent side apron member 28 as by screws 31''. The hinge arm 33 is likewise secured as by suitable screws 33' to the inside face of the adjacent rear leg extension 2'. As thus constructed, the seat section 25 is adapted to be folded into substantial parallelism with the back section 1 of the chair as indicated in Fig. 2.

The front leg section 5 is also hingedly connected to the seat section 25, as by a pair of front hinge assemblies 35. Each front hinge assembly 35 comprises a front seat bracket 36 which may be shaped from plate metal into angular form to present a front leg 37 secured as by screws 37' to the inside face of the adjacent front apron member 26, and a side leg 38 secured as by screws 38' to the inside face of the adjacent side apron member 28. A leg plate 40 formed from a stamped metal plate shaped into angular form to present a vertical leg 41 is secured as by screws 41' to the inside face of the upper portion of the adjacent front leg 6, and a horizontal leg 42 whose free end is hingedly secured to the side bracket leg 38 of the front seat bracket as by a pivot rivet 43.

Latching mechanism is also provided to retain the chair in rigid erect position. The latching mechanism, as indicated in Figs. 1 and 2, may comprise a latching bar 45 which extends horizontally along the inside face of the adjacent front apron member 26 and having the end portions thereof supported for sliding movement in a direction parallel to the seat panel 29 by suitable horizontal extending slots 39 provided in the side bracket legs 38 of the front hinge assemblies 35. Each of the leg plates 40 is provided with a latching notch 44 into which the adjacent end portion of the latching bar 45 may latch when the chair is in erect position with the latching notch 44 in alignment with the horizontal slots 39. A pair of coil springs 46, each having one end thereof attached to the adjacent end portion of the latching bar 45 and the other end thereof secured to the side bracket leg 38 of the adjacent front hinge assembly 35, provides means for resiliently urging the end portions of the latching bar 45 into latching engagement with the adjacent latching notches 44 to maintain the chair in rigid erect position.

An important feature of this invention is the provision of a rung frame comprising side rungs 8 which are normally out of reach of the feet of the chair occupant, and which are designed to automatically fold with the folding movement of the front leg section 5 to and from chair erected position. The paired side rungs 8 are connected together to provide a sturdy rung frame by one or more horizontally extending connecting bars 9 whose ends are fixedly secured to the approximate center section of the adjacent side rungs 8. Each side rung 8 has the rear end thereof hingedly connected to the adjacent rear leg 2 of the back section by a rear rung hinge assembly 10, and has the front end thereof hingedly connected to the adjacent front leg 6 of the front leg section 5 by a similarly constructed front rung hinge assembly 11.

Each rear rung hinge assembly 10 is so constructed as to permit the flat rear end 12 of each

side rung 8 to which it is attached to flatly abut against the adjacent face 13 of the rear leg 2 so as to provide only a hair line seam therebetween when the chair is in erected position. Similarly, each front rung hinge assembly 11 is so constructed as to permit the flat front end 14 of each side rung to which it is attached to substantially abut against the adjacent flat face 15 of the front leg 6 to provide a substantially hair line seam therebetween when the chair is in erected position.

The rear and front rung hinge assemblies 10 and 11 may be similar in shape and construction and may be economically formed from stamped metal parts as indicated more particularly in Figs. 3 to 7 inclusive. Each of the rung hinge assemblies 10 and 11 comprises a leaf plate 15 in the shape of a crescent presenting an arcuate edge 16' and a straight edge 16'' designed to be set into a conformed slot 17 in the end of the side rung 8 as indicated in Figs. 5, 6, and 7. Each of the rung hinge assemblies 10 and 11 also comprises a companion leaf plate 20 which is a substantial duplicate of the leaf plate 15 and is shaped in the form of a crescent presenting an arcuate edge 20' and a straight edge 20'' which is set into a conformed slot 21 in the adjacent chair leg. The leaf plate 16 is provided with a head portion 19 which projects laterally from one end of the straight edge 16'', thereof, and the companion leaf plate 20 is also provided with a similar head portion 23 which projects laterally from one end of the straight edge 20'', thereof. The head portions 19 and 23 of the leaf plates 16 and 20 respectively are arranged in overlapped relationship and pivotally connected together by a hinge rivet 24.

The leaf plates 16 and 20 pivotally connected by the hinge rivet 24 extending through the head portions thereof may be economically manufactured, since the leaf plates 16 and 20 may be similar in shape and design, with the rear hinge assemblies 10 and the front hinge assemblies 11 correspondingly similar and made from similar parts. The rear and front hinge assemblies 10 and 11 are constructed to be quickly and conveniently connected to the ends of the side rungs 8 and the adjacent chair legs. During manufacture of the side rungs 8, a conforming slot 17 is cut into the upper face 8' of each rung adjacent to rear end thereof to receive the rung leaf plate 16 of the rear hinge assembly 10, and a corresponding conforming slot 21 is cut into the under side 8'' of the front end of each side rung 8 to receive the rung leaf plate 16 of the adjacent front hinge assembly 11. During manufacture of the chair legs, a conforming slot 21 is also cut in the adjacent face 13 of the rear leg 2 to receive the leaf plate 20 forming a part of the rear hinge assembly 10, and a corresponding slot 21 is cut in the face 15 of the adjacent front leg to receive the leaf plate 20 of the associated front hinge assembly 11.

Each conforming slot 17 is shaped to receive the leaf plate 16 so that the straight edge 16'' of the leaf plate 16 which forms a part of the rear hinge assembly 10 is flush with the upper face 8' of the side rung 8, and the edge 16'' of the leaf plate 16 which forms a part of the front hinge assembly 11 is flush with the under face 8'' of the side rung 8. Similarly, the companion leaf plate 20 is set into the adjacent leg in a manner so that straight edge 20'' of the leaf plate 20 forming a part of the rear hinge assembly 10 is flush with the face 13 of the rear leg, and so

that the straight edge 20'' of the leaf plate 20 forming a part of the front hinge assembly 11 is flush with the adjacent face 15 of the front chair leg 6. Each leaf plate 16 is provided with a series of small holes 18 through which nails 18' may be inserted to secure the leaf plate to the side rungs. Similarly, each leaf plate 20 is also provided with a series of nail receiving holes 22 through which nails 22' may be inserted to secure the same to the chair leg.

As thus assembled, the leaf plates 16 and 20 forming a part of the rear and front hinge assemblies 10 and 11 are substantially invisible from exterior view, and only the head portions 19 and 23 thereof project outside of the faces of the side rungs and adjacent chair legs. When the chair is in erected position as indicated in Fig. 1, the pivotally connected head portions 19 and 23 forming a part of the rear hinge assembly 10 nest in the upper corner defined by the upper face 8' of the side rung 8 and the adjacent vertical face 13 of the rear leg 2 and are thus not appreciably visible. Similarly, the pivotally connected head portions 19 and 23 forming a part of front hinge assembly 11 nest in the lower corner defined by the lower face 8'' of the side rung 8 and the adjacent vertical face 15 of the front leg 6 and are thus substantially concealed from direct view. The hinge assemblies 10 and 11 are nevertheless so constructed as to permit unobstructed swinging movement of the side rungs 8 to and from the chair folded position as indicated in Fig. 2.

The rear and front hinge assemblies 10 and 11 are mounted as to permit the rear and front ends 12 and 14 of the side rungs 8 to substantially abut the adjacent rear and front leg faces 13 and 15 so as to reveal only a hair line seam therebetween when the chair is in erected position. The rung frame may be made from either wood or metal and the side rungs 8 as rigidly secured together by one or more connecting bars 9 provide a sturdy and rigid rung frame which is out of the way of the feet of the chair occupant and provides strong, sturdy and lasting bracing between the front and rear legs of the chair.

While certain novel features of this invention have been disclosed above, and are pointed out in the claims, it will be understood that various omissions, substitutions, and changes may be made by those skilled in the art without departing from the spirit of this invention.

What is claimed is:

1. In combination with a folding chair comprising a seat section, a back section having a pair of rear chair legs formed of wood material pivotally connected to said seat section, and a front leg section having a pair of front chair legs formed of wood material pivotally connected to said seat section, said seat section and front leg section being foldable into approximate parallelism with said back section of a foldable rung assembly, including side bracing rungs formed of wood material automatically foldable with the folding movement of said seat section, said side bracing rungs extending between the adjacent front and rear chair legs, front and rear hinge assemblies for pivotally connecting the ends of each of said side rungs to the adjacent legs in a manner to brace the legs when the chair is in erected position, each of said rung hinge assemblies comprising a pair of metal leaf plates, one of said leaf plates being embedded in a vertical conforming groove extending longitudinally into the adjacent end of the side rung and the companion leaf plate being embedded in a conform-

ing groove in the adjacent chair leg, means for fixedly securing the leaf plates of each hinge assembly to its associated side rung and chair leg respectively, said securing means including a plurality of slender metal pins driven laterally through spaced conforming holes in each of said leaf plates and into both wood portions on opposite sides of the leaf plate between which the leaf plate is embedded, said leaf plates having projecting head portions arranged in overlapped relationship and fitted within the corner formed by the adjacent face of the chair leg and the adjacent face of the side rung, and means for pivotally connecting said head portions in a manner to permit swinging movement of said side rungs.

2. In combination with a folding chair comprising a seat section, a back section having a pair of rear chair legs formed of wood material pivotally connected to said seat section, and a front leg section having a pair of front chair legs formed of wood material pivotally connected to said seat section, said seat section and front leg section being foldable into approximate parallelism with said back section, of a bracing rung formed of wood material extending horizontally between and connected to the upper half portions of the front chair legs and beyond the reach of the feet of the chair occupant, and a folding rung assembly including a pair of side bracing rungs formed of wood material automatically foldable with the folding movement of said seat section, said side bracing rungs extending between the adjacent front and rear chair legs, front and rear hinge assemblies for pivotally connecting the ends of each of said side rungs to the adjacent chair legs in a manner to brace the legs when the chair is in erected position and yet automatically foldable with the folding movement of said seat section, each of said rung hinge assemblies comprising a pair of metal leaf plates, one of said leaf plates being embedded in a vertical conforming groove extending longitudinally into the adjacent end of the side rung and the companion leaf plate being embedded in a conforming groove in the adjacent chair leg, means for fixedly securing the leaf plates of each hinge assembly to its associated side rung and chair leg respectively, said securing means including a plurality of slender metal pins driven laterally through spaced conforming holes in each of said leaf plates and into both wood portions on opposite sides of the leaf plate between which the leaf plate is embedded, each of said plates having a projecting head portion, said head portions being arranged in overlapped relationship and fitted within the corner formed by the adjacent face of the chair leg and the adjacent face of the side rung, and a pivot rivet for pivotally connecting said head portions in a pivoting assembly.

3. In combination with a folding chair of the type which includes a seat section, a back section

having a pair of rear chair legs formed of wood material pivotally connected to said seat section, a front leg section having a pair of front chair legs formed of wood material pivotally connected to said seat section, said seat section and front leg section being foldable into approximate parallelism with said back section, and latching mechanism for releasably retaining the chair in erected position, of a front bracing rung extending horizontally between and connected to the upper half portions of the front chair legs and beyond the reach of the feet of the chair occupant, and a rung frame automatically foldable with the folding movement of said seat section, said rung frame comprising a pair of side bracing rungs formed of wood material extending between the adjacent front and rear chair legs, front and rear hinge assemblies for pivotally connecting the ends of each of said side rungs to the adjacent chair legs in a manner to brace the legs when the chair is in erected position, and a connecting bar extending laterally of the chair between said side rungs and beyond the reach of the feet of the chair occupant with the ends thereof secured to the approximate mid-section of the adjacent side rungs, each of said rung hinge assemblies comprising a pair of metal leaf plates, one of said leaf plates being embedded in a vertical conforming groove extending longitudinally into the adjacent end of the side rung and the companion leaf plate being embedded in a conforming groove in the adjacent chair leg, means for fixedly securing the leaf plates of each rung hinge assembly to the associated side rung and adjacent chair leg respectively, said securing means including a plurality of slender metal pins driven laterally through spaced conforming holes in each of said leaf plates and into both wood portions on opposite sides of the leaf plate between which the leaf plate is embedded, each of said leaf plates having a projecting head portion, said head portions being arranged in overlapped relationship and fitted within the corner formed by the adjacent face of the chair leg and the adjacent face of the side rung, and a pivot rivet for pivotally connecting said head portions in a manner to permit swinging movement of said rung frame.
